UNITED STATES PATENT OFFICE.

MAURICE F. AARON, OF MIZPAH, NEW JERSEY.

AUTOMOBILE SEAT-CUSHION COVER.

Application filed May 29, 1925. Serial No. 33,720.

This invention relates to improvements in seat cushion covers for automobiles and more particularly to a cover for use in conjunction with individual seat cushions.

5 One of the important objects of the invention is to provide a cover which is of such construction as to enable the same to fit snugly and properly on the cushion, additional means being associated therewith for 10 preventing the creeping of the cover with respect to the cushion and seat.

A still further object is to provide a seat cushion cover which may be readily and easily attached and will not in any way be 15 secured to the material forming the cushion.

A further object is to provide a cover for the usual hinged back rest associated with the individual types of seats which are used in automobiles of the closed type.

20 A still further object is to provide a seat cushion cover of the character above described which is simple in construction, inexpensive, strong and durable and furthermore adapted for the purpose for which it 25 is designated.

Other objects and advantages of this invention will become apparent during the course of the following description.

In the accompanying drawing forming a 30 part of this specification and in which like numerals designate like parts throughout the same:

Figure 1 is a perspective view of the cover for the back rest.

35 Figure 2 is a detail perspective view of the cover for an individual seat cushion.

Figure 3 is a fragmentary top plan of the flap associated with the cover for the back rest showing one of the elastic straps with 40 the snap fastener elements associated therewith, and

Figure 4 is a fragmentary plan of one of the corners of the cover for the seat cushion.

In the drawing, wherein for the purpose 45 of illustration is shown the preferred embodiment of my invention, the numeral 1 designates generally my improved cushion cover, the same being formed of any suitable fabric. The piece of fabric which is 50 adapted to cover the top of the seat cushion is indicated at 2 and the ends of this piece of fabric are adapted to provide the front and rear flaps 3 and 4 respectively. The side flaps which cover the sides of the individual seat cushions are indicated at 5 and 55 the same are stitched at their upper edges

to the respective longitudinal edges of the teeth 2, the forward edges of the side flaps being stitched to the side edges of the front flap 3, thus rendering the rear flap 4 free. 60 A binding such as is shown at 6 extends around the free edges of the flaps as also clearly illustrated in the drawing with reference more particularly to Figures 2 and 4. 65

Secured on the outer sides of each of the side flaps 5 adjacent the rear free end thereof is one end of a piece of elastic 7. The male section 8 of any well known form of snap fastener is carried by the free end of each 70 of the elastic straps. Cooperating with the male sections 8 are the female sections 9 of the snap fasteners, the female sections being secured to the rear flaps 4 adjacent the respective sides thereof, it being understood 75 of course that the ends of the side flaps which are free are disposed inwardly of the rear flap 4 and will be interposed between the rear flaps and the back of the seat cushion when the cover is attached. It is 80 also to be understood that suitable reinforcing means is associated with the side flaps at the point where the elastic bands are secured thereto and also with the rear flaps 4 at the points where the female sections 9 85 of the snap fasteners are secured.

The purpose of the elastic bands 7 is to take up any looseness which may occur when the cover is placed over the cushion as it is very difficult in cutting the covers to 90 match the seat cushions to obtain the exact measurements and oftentimes the cover will not fit snugly on the cushion. Furthermore, the elastic bands permit the adjustment of the flaps with respect to the seat cushion 95 so as to enable the cover to fit snugly over the seat cushion.

In order to prevent the accidental displacement of the cover from the cushion and to further prevent creeping, suitable 100 loops such as are shown at 10 are associated with the lower edges of the flaps of the cover and are adapted to be secured to the seat underneath the bottom of the cushion by suitable tacks or the like. 105

Cooperating with the seat cushion cover 1 is the cover 11 which is provided for the usual hinged back rest associated with the individual seats of an automobile of the closed type. The cover 11 is open at its bottom, a flap 12 being stitched to the lower edge of the portion of the cover which ex- 110

tends over the front of the back rest. The flap 12 has its side edges terminating at a point inwardly from the sides of the cover so that the cover may be properly placed 5 over the back rest without interfering with the hinges. The flap 12 will thereby be disposed between the usual hinges associated with the back rest. Elastic straps 13 are secured at their upper ends to the lower edge 10 of the front portion of the cover and the lower free end of the elastic straps have associated therewith the male sections or members 14 of suitable snap fasteners, the female sections or members 15 being secured 15 to the back portion of the cover 11 adjacent the lower edge thereof. The purpose of the elastic bands 13 is similar to that of the elastic bands 7 and it is not thought necessary to go in further detail relative to the 20 same. It is also to be understood that similar reinforcing means is associated with the cover 11 for the same purposes as the reinforcing means which is provided in connection with the seat cover.

25 It will thus be seen from the foregoing description, that a seat cushion cover and a back rest cover have been provided, the same being of such construction as to facilitate the attaching of the same on or the removal from the seat cushion and back rest 30 respectively without the loss of any considerable length of time or labor.

While I have shown the preferred embodiment of my invention, it is to be understood that various changes in the size, shape 35 and arrangements of parts may be resorted to without departing from the spirit of the invention and the scope of the appended claim.

Having thus described the invention, what 40 I claim is:

A seat cushion cover comprising a piece of fabric adapted to cover the top of the seat cushion, and including front and rear flaps, side flaps stitched along their upper 45 edges to the side edges of the piece of fabric which covers the top of the seat cushion, the forward edges of the side flaps being stitched to the side edges of the front flap, the rear free ends of the side flaps being disposed inwardly and interposed between the rear flaps and the back of the seat cushion, an elastic strip secured at its forward end to the outer side of each of the side flaps adjacent the rear free end thereof, cooperating detachable 50 securing means associated with the free end of each elastic strip, and the adjacent end of the rear flap, and loop members associated with the lower edges of the flaps for facilitating the attachment of the cover to 55 the seat below the cushion.

In testimony whereof I affix my signature.

MAURICE F. AARON.
